CLAIM

The ornamental design for a combined perfume bottle and cap, as shown and described.

DESCRIPTION

FIG. 1 is a perspective view of a combined perfume bottle and cap according to the invention;

FIG. 2 is a front elevation of the combined perfume bottle and cap, the rear elevation is the same;

FIG. 3 is a side elevation, the opposite side is the same; FIG. 4 is a top plan view; and

FIG. 5 is an underside view of the combined perfume bottle and cap according to the invention. The broken lines shown in FIG. 5 are for illustrative purposes only and do not form part of the claimed design.
